UNITED STATES PATENT OFFICE.

GUST NELSON, OF VANCOUVER, BRITISH COLUMBIA, CANADA, ASSIGNOR OF ONE-HALF
TO FRANK R. PENDLETON, OF VANCOUVER, CANADA.

CONVEYER.

Application filed December 2, 1926. Serial No. 152,272.

My invention relates to improvements in conveyers which are particularly adapted for conveying large logs such as are cut on the Pacific slope, from the point where they are 5 logged and yarded, to a delivery station at a lower elevation. The objects of the invention being to provide a carriage, preferably moved by gravity along an inclined aerial track, to which a load is raised and carried; 10 to provide for the automatic release of the load as the carriage reaches its destination, and to provide means for preventing the carriage from displacement from its track.

The invention consists essentially of a carriage endwise movable along an aerial track having means for raising, transporting and lowering a load, a carriage retaining device at one end of the track, and means at the other end of the track with which the carriage is 20 adapted to form a contact, to release the load, means for returning the carriage to starting point and means for raising and locking a further load to the carriage, as will be more fully described in the following specification, 25 in which:—

Fig. 1 is a general view of the invention.

Fig. 2 is a fractionated view of the carriage, the retaining block and the bumper block.

30 Fig. 3 is a plan view taken on the line 3—3 of Figure 2.

Fig. 4 is a sectional view taken on the line 4—4 of Figure 2.

35 Fig. 5 is a plan view of the movable track guard.

Fig. 6 is a sectional view of the track saddle.

Fig. 7 is a view showing a choker line suspended from a hoisting block.

40 Fig. 8 is a view showing the manner in which the choker is attached to the log and the manner of its release.

In the drawings like characters of reference indicate corresponding parts in each 45 figure.

The numeral 2 indicates an aerial track which extends between a spar tree 3 situated at a point where the logs are assembled for transportation and a further spar tree 4 50 situated at a suitable delivery point. The track is preferably set to such an inclination as to permit the carriage to run when loaded from the point of assembly to the delivery point by gravity, but it will be obvious that 55 where insufficient grade is available, means

may be adopted to impart the necessary movement thereto. Intermediate support for the cable may be introduced by providing an arm 5 fulcrumed intermediate its length as at 6 to a post 7, the outer end of the arm 5 being 60 anchored back to the post by a flexible connection 8 having a tension spring 9. The outer end of the arm 5 supports a saddle generally indicated by the numeral 10, see Figure 6, which is splayed downwards towards its ends and is provided with a groove 11 to receive the track cable 2. The track is held in position within the groove 11 by a metal cover 12 which extends downwards on opposite sides of the saddle 10 and is secured thereto 65 by a bolt 13 or other suitable fastening.

The numeral 14 indicates generally a carriage having a beam 15 connecting together a pair of hangers 16, see Figure 4, each of these hangers is provided with a pivotally 70 mounted frame 17 at its upper end in which a pair of track sheaves 18 are journalled. The lower portion of each hanger forms a bell shaped block housing 19 having a rectangular aperture 20 at its upper extremity of a size 75 equal to the cross sectional area of the hoisting block hook shank, which will be described hereinafter. Adjacent the upper end of the housing 19 a hinged flap 21 is fitted, the upper extremity of the flap forms one side wall to the aperture 20, and is adjustably sprung tensioned as at 22 to hold the flap normally in closed position as shown in Figure 4. Extending along the beam 15 is an endwise movable latch rod 23, see Figures 2, 3 and 4, having adjacent its ends a pair of slots 24 which are adapted to register with the apertures 20 of the housing 19 when moved in a rearward direction. Upon the forward end of the carriage 14 is a spring tensioned trigger 25 connected to one end of the latch rod 23. On the rear end of the carriage 14 a trip catch 26 is mounted upon a pin 27, the free end of this catch is capable of a limited lateral and vertical movement and is held in relatively fixed 80 position by a spring 28 upon the pin 27. Upon the top of the beam 15 and below the track 2 is a guard 29 having laterally curved ends 30, see Figure 5, which are adapted to project beyond the width of the track 2 or the track saddle 10. The guard is hingedly mounted as at 31 and is provided with tension springs 32 to hold it in normal position below the track 2 and in such close proximity thereto, as to prevent a sudden jar of the carriage, 85

such as would occur when the load is suddenly released, from throwing the sheaves 18 off the track. By providing the curved ends 30 to the guards 29, it is moved about its hinge 31 on striking the saddle 10 so as to prevent the guard from forming an obstruction to the free passage of the carriage along the track 2 and its saddle 10. Suspended from the lower edge and one side of each of the block housings 19 is a pair of chains 33 which are spaced apart at intervals of their lengths by flights 34, the purpose of which will hereinafter appear. At the delivery point of the track 2 a suitably anchored stop 35 is mounted, which is suspended from a pair of sheaves 36 for the purpose of preventing the block movement due to carriage impact from producing undue wear upon the track, at the rearward end of the block a spring tensioned bumper 37 is fitted, which is adapted to be engaged by the trigger 25 of the carriage 14, as the carriage comes to rest at the end of its downward travel.

At the assembly point of the track 2 a retaining block 38 having track sheaves 39 is mounted and is suitably anchored against undue movement along the track. A pocket 40 is formed in the retaining block which presents a bell mouth towards the carriage and is adapted to receive the trip catch 26 thereof. The pocket 40 is provided with a spring tensioned arm 41 fulcrumed adjacent its forward end as at 42, which is adapted to exert a resilient pressure upon the trip catch 26 outwards from the line of the track to hold it in firm contact with a release dog generally indicated by the numeral 43. The release dog 43 is fulcrumed on a vertical pin 44 carried in the pocket 40 and is provided with a rearwardly extending projection 45 which is adapted to lie, when the trip catch 26 is in the pocket, in contact with the outer extremity of said catch. The dog 43 is provided with a spring tensioned lever 46 to which a line 47 leading to a suitable control position, is attached.

The outer end of the trip catch 26 when in engaged position with the dog 43 is adapted to project laterally outward beyond the fulcrum pin 44, so that the pull exerted by the carriage 14 will not tend to release the trip catch from the dog, and further, when it is desired to effect such release a pull exerted on the line 47 rocks the dog 43 and its extension 45, which latter presses the trip catch 26 back against the spring tensioned arm 41 and out of engagement with the dog, so that the carriage may move downwardly along the track 2 and withdraw the trip catch from the pocket 40.

The numeral 48 indicates a pair of hoisting blocks each of which is provided with an upwardly extending shank 49 having a pointed latch member 50 at its upper end which is adapted to pass through the top opening of the housing 19 of the carriage and to engage the top surface of the latch rod

23 adjacent one of its slots 24. The lower end of the block 48 is weighted as at 51 for the purpose of holding the shank 49 in vertical position when the block is being raised either with or without load, a shackle 52 or other fitting is mounted at the lower end of the weight 51 as a means of fastening to a choker line 53, which line is adapted to be passed round the log to suspend it from the carriage. The blocks 48 are suspended from their housings by hoisting lines 54 which are connected at one end to the inside of the housings, the lines passing first through the sheave of the block thence over suitable sheaves mounted upon the carriage and back to a head block, 80 not shown, on the spar tree 3 and from thence are wound onto a drum of a winding engine, or are connected together and attached to a single line which would lead to a drum. The choker line 53 is fitted with choker hook, see 85 Figures 7 and 8, consisting of a running shackle 55 having a pivotally mounted lever 56 which is provided with a downwardly and inturned hook 57 adjacent its fulcrum and upon the free end of the choker line is a fitting 58 having an eye 59 which is adapted to be engaged by the hook 57 to secure the log in the bight of the choker line 53. The lever 56 is adapted to extend transversely and to be inclined downwardly from the log when 95 in normal engaging position as shown in Figure 8.

Having thus described the several parts of my invention I will now briefly explain its operation.

Assuming the carriage to be held at the assembly point and ready to load the lines 54 are slackened off from the winding drum to lower the hoisting blocks 48 down to the log to be transported, the choker lines 53 are then passed around the log and the eyed fittings 58 slipped over the hook member 57 of the levers 56 to secure them about the log. The drum is rotated to haul in the lines 54 to raise the load. Should the load be to one side of the track prior to lifting, it will obviously follow that the carriage will assume an inclined position as the initial tightening of the hoisting lines is effected, but since the retaining block 38 is freely suspended from the track 2 it can assume a similar angle to that of the carriage without in any way affecting the carriage releasing means. As the pull on the lines is continued the load is raised towards the carriage, and the levers 56 on the choker lines will successively pass the flights 34 of the chains 33 until the ultimate height of load is reached when the said levers will project between some of the flights in a position to be obstructed thereby on the downward movement of the load, as shown in Figure 8. The final upward movement of the load will cause the upstanding shanks 49 of the load block to press open the hinged flaps 21 against 125

their spring tension 22 and to pass through the apertures 20 in the upper portion of the housings 19, which shanks will slide transversely into holding engagement with the 5 latch rod 23, so that the strain on the lines 54 may be entirely released and the load locked in elevated position as shown in Figures 1, 2 and 4. The winding drum is then released or rendered free to rotate as desired 10 and a pull is exerted on the release line 47 to rock the dog 43 about its pin 44 and to release the trip catch 26 secured to the carriage. The carriage is then free to run by gravity, or to be otherwise moved towards 15 the delivery point. As the carriage 14 approaches a saddle 10, the outer end of the arm 5 is depressed by the increase of weight on the adjacent portion of track so that the inclination of the track at such approach is 20 reduced, with the result that the carriage passes over the saddle without undue impedance to speed of travel or vertical movement which might otherwise tend to cause the sheaves of the carriage to jump the track 2. 25 If the downward inclination of the track is such as to cause the carriage to run at excessive speed, a braking effect is imposed upon the winding drum sufficient to reduce the speed to within convenient speed limits. As 30 the carriage reaches the stop block 35 the trigger 25 is overrun by the carriage 14, causing the latch rod 23 to move so that its slots 24 register with the apertures at the upper end of the housings 19, thus releasing the 35 hoisting blocks from their locked position to the carriage and the load suddenly being transferred through the blocks 48 to the lines 54 which increases the speed of the winding drum permitting additional cable to be paid 40 out to lower the blocks and their load.

As the load is pulling the blocks in a downward direction the outer ends of the choker line levers 56 are held against corresponding downward movement by the flights 34 of the 45 chains 33, whereas the inner ends of the levers continue downward, releasing their hooks 57 from the eyed fittings 58 of the choker line 53 so that the log is automatically detached from the carriage and falls to the ground. 50 As soon as the load is detached the loading blocks cease to fall, so that no further line is paid out.

The carriage is hauled back to starting

point by winding in the lines 54 upon the drum its initial movement permitting the return of the latch rod 23 to normal position with its slots 24 out of register with the apertures 20 of the housings 19, the initial winding causing the shanks 49 of the loading blocks to enter the housing 19 and their extremities to reach the apertures 20 thereof, but are prevented projecting therethrough by the pressure of the spring 22 which is of such tension as to hold the flap 21 closed and to cause the tension of the lines 54 to draw the carriage rearwards along the track or until it has come to rest with its trip catch 26 engaged within the pocket 40 of the retaining block 38. When this position is reached by 70 the carriage and the carriage locked against movement, the lines 54 may be slackened and the load blocks lowered for the attachment of a further load or log.

What I claim as my invention is:

A conveyer comprising a traveling carriage including a beam, a pair of hangers secured to opposite ends of said beam, the lower portion of each hanger being formed to provide a block housing having an aperture at its upper extremity, an upper wall portion 80 of each housing being hingedly mounted to form a flap having its upper edge disposed to constitute one margin of said opening, a spring arranged to exert inward pressure on said flap, a longitudinally movable latch rod 85 slidably mounted on said beam with one edge of the latch rod overhanging a portion of the opening formed in each block housing, the said edge of the latch rod being provided with slots adapted at times to register with 90 said openings, and a pair of load blocks provided each with a shank adapted to be passed upwardly through the opening of one of said housings between the latch rod and the hingedly mounted flap and provided with a projection adapted to hook over the latch rod to support the shank and block in elevated position, and means for shifting the latch rod to position the slots therein beneath the latch projections of said shanks and in registration with said openings to permit downward movement or withdrawal of the shanks 100 from the housings.

Dated at Vancouver, B. C., this 12th day of November, 1926.

GUST NELSON.
